HENRY L. WALBRIDGE, OF NEW YORK, N. Y.

WRAPPING AND CHECK APPARATUS FOR STORE-SERVICE.

1,118,318.

Specification of Letters Patent. Patented Nov. 24, 1914.

Application filed July 30, 1913. Serial No. 781,930.

To all whom it may concern:

Be it known that I, HENRY L. WALBRIDGE, a citizen of the United States of America, and resident of New York, in the county of New York and State of New York, have invented certain new and useful Improvements in Wrapping and Check Apparatuses for Store-Service, of which the following is a full, clear, and exact description.

10 One of the objects of this invention is to provide means for preventing the improper use or waste of wrapping paper by clerks and sales people, where the paper is stored in the form of rolls as is usually the case; 15 which is brought about by requiring a record of a substantially permanent form to be made and retained, of each portion or section of the material as it is unrolled and withdrawn or severed from the roll. 20 A further object of the invention is to cause a record of each sale of the articles that are wrapped up in the sections of the paper or other material from the roll, to be made on such section of the roll, and at the 25 same time on a marginal portion, either of the roll itself, or of a separate web or roll that is wound up with the roll of material; and which can be effected by the use of a transfer device, such as the usual carbon 30 paper employed in making duplicates of any written or typed matter.

Another object of this invention is to provide means for making duplicate sales records, by having a superposed pair of 35 webs wound up in the form of a roll, and to provide means for the rewinding of one of the webs as they are both unwound, after a record is made, by a transfer or carbon sheet in duplicate on the two webs; the other of 40 the two webs being removed for use with the articles purchased.

A further object of the invention is to provide in a device of the described character, means whereby as the roll is unwound, and 45 a duplicate of a sales form has been made by the clerk on the marginal portion and at the same time on a narrow web, that is either a portion of the original roll, or a separate superposed web such portion will be automatically rewound to form a permanent record for future use.

A further object of this invention is to provide as an article of manufacture, a roll of wrapping paper provided with a longi-

tudinal line of perforations near one of its 55 margins, and to also provide at short intervals, lines of perforations extending from said line across the sheet to the edge farthest removed from the longitudinal line of perforations.

60

Another object of the invention is to provide in the several forms above set forth printed matter in the nature of sales forms, at short intervals along the web, one for each portion that is to be severed or removed; and which sales forms are in duplicate on the rolls and on the portion that is rewound to form the permanent record.

65

In the accompanying drawing illustrating embodiments of my invention, Figure 1 70 shows a side elevation. Fig. 2 is a plan view at one end portion of the device as shown in Fig. 1. Fig. 3 shows the structure of Fig. 1 in the matter of making a duplicate record. Fig. 4 shows a modification. Fig. 5 is a side 75 elevation, and Fig. 6 a plan of another modification.

70

In the form shown in Fig. 1 a roll 12 of wrapping material such as paper is shown wound around a shaft 13 that is supported 80 at its extremities by a pair of brackets 14 only one of which is shown in Figs. 1 and 2; these brackets being provided with a slot 15 into which the shaft 13 extends. The brackets 14 at the lower portions support a 85 second shaft 16, parallel with the shaft 13. The roll of material 12 is shown as provided with a line of perforations 17 near one of its sides, and as the material is drawn from the roll it is severed at this line to form a marginal web or roll 18; and as the material is first unwound the end of this narrow web 18 is wound up on the shaft 16, as indicated 90 in Figs. 1 and 3.

90

By reason of the shaft 13 for the roll 12 95 being vertically slidable in the slots 15 in the brackets 14, the roll 12 will move downward until the two rolls, 12 and 18' are in peripheral contact, and the weight of the upper roll will be largely carried by the 100 smaller roll,—so that as the material is drawn off the roll 12 and rotates it, the roll 18' will be rotated in the opposite direction, that will cause the narrow web 18 to automatically wind itself around the shaft 16 as 105 fast as the material is drawn off from the roll 12.

If desired the severing of the smaller web

- 2 along the line 17 may be effected by means of a small cutter 19 that is pressed against this line on the roll 12 by means of a spring arm 20, at the back of the device, where the 5 two brackets 14 may be secured to a plate 21. If desired lines of perforations 22 may be provided extending transversely from the 10 said lines of perforations 17 across the web to the opposite side, to facilitate the severing 15 of the web into sheets for use. The marginal portion 18 of the roll 12 may also be provided with printed matter such as sales forms as shown at 23, at short intervals, and the main portion 12 may also be provided 20 with duplicate sales forms on the opposite edge and on the under face of the web, so that when the sheet is severed by a knife or blade along the line 22 as shown in Fig. 3, it can be folded over as indicated in Fig. 3 25 to bring the duplicate sales form 24 on the under face of the sheet, on top of the sales form 23; and by interposing a transfer device such as a carbon sheet 25 between these 30 two portions, a record made by the clerk in the form on the folded portion 12, will be duplicated on the form 23 of the web 18. Forms 23 and 24 are serially numbered as 35 shown. It will be understood that after such record is made the unwinding of another portion from the roll 12 will cause this record on the form 23 to be wound up on the roll 18 and thereby a permanent record is made as each section of the roll 12 is unwound and removed; it being understood 40 that these duplicate forms, 23 and 24 are spaced apart, one between each of the lines of severance 22; and these sales forms may further be numbered in serial order if desired.
- 40 In the arrangement shown in Fig. 4 the longitudinal line of perforations 17 is not employed and instead of the narrow web 18 that is a part of the roll 12, the main roll 30 in this form is provided with a supplemental narrow web 31, these two being superposed as they are wound up to form the roll 32; and as the portion 30 is withdrawn the smaller web 31 will be wound up into a roll 33, by the peripheral contact of the two rolls 32 and 33; 45 which are supported by brackets similar to the brackets 14 which I have described. In this form also, a transfer or carbon sheet 25 is interposed between the main web 30 and the smaller web 31, at the top of the roll, for making the duplicate record of a sale by the clerk, before the sheet is unrolled and severed. In this form the main web 30, and the record web 31, may be provided with 50 sales forms 34 and 35 that will register on the roll as the record is made thereon. The web 30 may also be provided with transverse lines of perforations 36 that in this case will extend entirely across the web. Instead of the clerk writing by hand the sales 55 record on the forms, or on the superposed webs, any form of a writing machine could be arranged at the top of the roll, so that the record might be even made in typewriting on the two superposed sheets or webs having the carbon sheet between them. 70
- 70 In the arrangement shown in Figs. 5 and 6 I provide a roll 40 supported in brackets 14, which roll is in the form of a pair of superposed webs 41 and 42, similar to the arrangement of Fig. 4, except that the two webs are of the same width; the web 41 being rewound on a shaft 43 to form a roll 44, while the other web 42, after the duplicate record is made, by the carbon sheet 45 is severed; and the latter may be provided 80 with transverse perforations 46 at such intervals. The transfer or carbon sheet 45 is shown as supported on each side by a link 46 connected with the back 47 of the bracket member, so that the transfer sheet will not 85 be pulled forward with the webs as unwound, yet the transfer sheet can shift as the diameter of the roll decreases. The two webs 41 and 42 can be provided with sales forms 48 similar to the form 23, but which 90 extend across the web 42, that forms no part of a wrapper sheet, but is merely a sales check that is given to the customer or attached to the article sold. With this arrangement for each check slip that is made 95 and severed, a duplicate is made on the web 41, that is automatically wound up on the roll 44, and thereby a permanent record is retained. With this arrangement the transfer or carbon sheet is maintained in its 100 proper position for use, and the only operation required is to draw out on the upper web 42 and tear off the check slip after being written, as the duplicate slip automatically rewinds itself on the lower roll, and is thus 105 prevented from being lost or mislaid. With the latter arrangement, any form of a writing device could be employed, such as the usual form of typewriter, or even the machine known as a book typewriter, that automatically travels across a stationary sheet or form to do the writing or printing. 110
- 110 What I claim is:—
1. The combination of a frame, a shaft supported on the frame to rotate in a fixed 115 position, a second shaft supported by the frame parallel with said shaft and guided to move to and from said shaft, and a cutter adjacent the second shaft arranged to longitudinally slit the material as it is unrolled from the second shaft into two webs. 120
2. The combination of a frame, a shaft supported on the frame, a second shaft on the frame parallel with said shaft and guided to move to and from said shaft adapted 125 to carry a roll of material, a transfer sheet supported adjacent a roll on the second shaft, and a cutter arranged adjacent the second shaft to slit material as it is unrolled from the second shaft into two webs. 130

3. The combination of a frame, a shaft rotatable on the frame, a second shaft supported for movement toward and from the other shaft, to carry a roll of wrapping material adapted to have a portion at one edge thereof severed and wound on the other shaft, and upon which severed portion a record is adapted to be made, said rolls being in peripheral contact whereby as the material is drawn off from the second shaft the said severed edge portion will be wound upon the other shaft.
4. The combination of a frame, a shaft rotatable on the frame, a second shaft on the frame parallel with said shaft and guided to move to and from the shaft, to carry a roll of wrapping material adapted to have a portion at one edge thereof wound on the other shaft, said rolls being in peripheral contact whereby as the material is drawn off from the second shaft the said edge portion is wound up on the other shaft, and a cutter supported adjacent the said roll of material to slit the material into two webs as it is drawn off.
5. The combination of a frame, a shaft rotatable on the frame, a second shaft on the frame supported for movement to and from the other shaft, to carry a roll of wrapping material adapted to have a portion at one edge thereof wound on the other shaft, the rolls being in peripheral contact whereby as the material is drawn off from the second shaft the said edge portion will be wound upon the other said shaft, and a carbon sheet supported adjacent the roll of material on the second shaft arranged to cause a record made upon the material to be impressed on said edge portion of the material.
6. The combination of a frame, a shaft on the frame, a second shaft on the frame supported for movement to and from the other shaft, to carry a roll of wrapping material, a cutter adjacent the said roll of material to sever it into two webs as it is unrolled, one of said webs being engaged by the other shaft to be wound thereon by peripheral contact with said roll as the material is unwound therefrom.
7. The combination of a frame, a shaft on the frame, a second shaft on the frame supported for movement to and from the other shaft, to carry a roll of wrapping material having a line of perforations extending longitudinally at one side permitting the roll to be severed in two webs as unwound, one of the webs being attached to the other shaft to be wound thereon by the peripheral contact of the two rolls.
8. The combination of a frame, a shaft on the frame, a second shaft on the frame supported for movement to and from the other shaft, to carry a roll of wrapping material having a line of perforations extending longitudinally at one side permitting the roll to be severed into two webs, one of the webs being attached to the other shaft to be wound thereon by the peripheral contact of the two rolls, and a transfer sheet adjacent the material on the second shaft arranged to cause a record as made upon the one web to be impressed upon the other web.
9. The combination of a frame, a shaft on the frame, a second shaft on the frame supported for movement to and from the other shaft, to carry a roll of wrapping material having a line of perforations extending longitudinally at one side permitting the web to be severed into two webs, a cutter arranged to slit the material at said perforations as unwound, one of the severed webs being attached to the other shaft to be wound thereon by the peripheral contact of the two rolls, and a transfer sheet adjacent the material on the second shaft arranged to cause a record to be made upon one web to be impressed upon the other web.
10. The combination of a frame, a shaft on the frame, a second shaft on the frame supported for movement to and from the other shaft, to carry a roll of wrapping material having a line of perforations extending longitudinally at one side permitting the roll to be severed into two webs as unwound, one of the severed webs being attached to the other shaft to be wound thereon by the peripheral contact of the two rolls, and a line of perforations at intervals on one web extending from said line across the web to the opposite edge.
11. The combination of a frame, a shaft on the frame, a second shaft supported by the frame for movement toward and from said first shaft to carry a roll of wrapping material having sales forms in duplicate at equally spaced intervals and having a line of perforations extending longitudinally at one side to permit the material to be severed into two webs as unwound, said rolls being in peripheral contact whereby as the material is drawn off from the roll the said severed edge portion will be wound up on the first shaft, means to sever one web transversely, and a transfer sheet adjacent the material on the second shaft arranged to cause a record as made upon the one web to be impressed upon the other web.
12. The combination of a frame, a shaft on the frame, a second shaft on the frame supported for movement to and from the other shaft, to carry a roll of wrapping material having a line of perforations extending longitudinally at one side permitting the roll to be severed in to two webs as unwound, and having sales forms at equally spaced intervals on opposite sides of the line of perforations: one of the severed webs being attached to the other shaft to be wound thereon by the peripheral contact of the two rolls, and a transfer sheet to cause a record to be

made on the web attached to and wound on the one shaft.

13. The combination of a roll of wrapping material supported to have rotative and radial movement, a shaft parallel with said roll and upon which the roll has peripheral contact, means to longitudinally sever the wrapping material adjacent one edge as it is drawn from the roll, and upon which severed portion a record is adapted to be made and said shaft adapted to be rotated and the severed portion wound thereon by the peripheral contact of the roll upon said shaft and the material wound thereon.

14. The combination of a frame to rotatably support a roll of wrapping material and to have radial movement, a shaft sup-

ported by the frame parallel with the roll with which the roll has peripheral contact, means to longitudinally sever the wrapping material adjacent one edge as it is drawn from the roll and upon which severed portion a record is adapted to be made, said shaft being rotated and the severed portion of the material wound thereon by the peripheral contact of the roll of material upon said shaft and the material wound thereon, and a cutter adjacent the roll of material to sever the same transversely.
